UNITED STATES PATENT OFFICE.

THOMAS HOYLE, OF PROVIDENCE, RHODE ISLAND, ASSIGNOR TO JEWELERS AUTO EMBLEM MANUFACTURING CO., OF PROVIDENCE, RHODE ISLAND, A TRUST.

DESIGN FOR AN EMBLEM.

51,096.

Specification for Design. Patented July 31, 1917.

Application filed May 31, 1917. Serial No. 172,110. Term of patent $3\frac{1}{2}$ years.

To all whom it may concern:

Be it known that I, THOMAS HOYLE, a citizen of the United States, residing at the city and county of Providence, State of Rhode Island, have invented a new, original, and ornamental Design for an Emblem, of which the following is a specification, reference being had to the accompanying drawing, forming part thereof.

The figure is a face view of an emblem illustrating my new design.

I claim:

The ornamental design for an emblem as shown.

THOMAS HOYLE.

Witness:

HOWARD E. BARLOW.
